UNITED STATES PATENT OFFICE.

CARL E. BISHOP, OF MITCHELLVILLE, IOWA.

BOILER FOR STEAM ENGINES AND THE LIKE.

Application filed July 30, 1923. Serial No. 654,619.

To all whom it may concern:

Be it known that I, CARL E. BISHOP, a citizen of the United States, and a resident of Mitchellville, in the county of Polk and 5 State of Iowa, have invented a certain new and useful Boiler for Steam Engines and the like, of which the following is a specification.

The purpose of my invention is to provide 10 a boiler for the generation of steam for use in engines.

A particular object of my invention is to provide a boiler of the type under consideration in which the construction is such as to insure 15 the taking off of dry steam only for operating an engine or for other purposes. This purpose is accomplished by taking the steam off at a number of points, passing it along a path or through passages thoroughly 20 heated and of such size as to insure that all moisture is taken out of the steam before delivery to the throttle or the like.

This structure is of importance to insure 25 a practical boiler for use in steam vehicles, tractors and aeroplanes, or the like where space for installation is limited, where rapid formation of steam is necessary and light weight is a great advantage.

Another purpose is to provide means for a 30 large reserve of dry steam distributed through the boiler and to insure subjection of reserve steam to intense heat at the lower end of a vertical receptacle, without throttle action.

Another object is to provide a boiler of 35 such construction that it may be filled with water almost to the top for thereby avoiding or preventing the loosening of the threaded portions by contraction and expansion, such as occurs in boilers of low water level.

Another object is to provide such an arrangement of those steam tubes or passages, which are immediately subjected to the heat 45 of a burner, as to provide for a very great amount of metal for conducting heat and for preventing the burning out of these particular tubes.

Another object is to provide such a construction in which threaded coils or elements 50 may be employed, and generally in which the parts are so constructed and arranged as to facilitate the assembling or disassembling and repair of the structure.

My object is also to provide a boiler struc-

ture, such that in its circulation, the water takes its natural and normal path of least resistance.

I have not attempted here to state all of the objects of my invention, but with these 60 and other objects in view, my invention consists in the construction, arrangement and combination of the various parts of my device, whereby the objects contemplated are attained, as hereinafter more fully set forth, 65 pointed out in my claims, and illustrated in the accompanying drawings, in which:

Figure 1 shows a top or plan view of a boiler embodying my invention.

Figure 2 shows a vertical, sectional, detail 70 view taken on the line 2—2 of Figure 1.

Figure 3 shows a detail, sectional view taken on the line 3—3 of Figure 1.

Figure 4 shows a top or plan view of the steam reserve pipes with the other parts of 75 the boiler removed; and

Figure 5 shows a vertical, sectional view of the water receiving portion of a slightly modified form of my boiler.

My improved boiler consists, generally 80 speaking, primarily of what I may call the water container structure or water tank, the heating coils, and the steam reserve members.

The water container is that portion to 85 which the cold water is supplied, which is on the outside of the boiler and may be made in a variety of forms.

As shown in the drawings, the water container consists of a lower, annular tubular 90 water container, header or drum, indicated in the accompanying drawings by the reference character 10, and an upper spaced similar container 11.

The members 10 and 11 are connected by 95 a series of circumferentially equi-distantly spaced tubes 12.

The water container might be in the form of a continuous annular water jacket or it might be in the form of the lower member 100 10 having projecting upwardly therefrom a series of pipes or tubes 12^a, as shown in the modified form in Figure 5.

For receiving the water, I provide an enlarged stand pipe 13. The stand pipe 13 105 communicates with the members 11 and 10 in the preferred form of my invention, and has one or more intake tubes 14.

At the bottom of the stand pipe 13 is a removable plate 15 and at the top is a simi- 110

lar plate 16 held in place by screw bolts 17 and provided with suitable copper gaskets or the like.

It will thus be seen that all the pipes 12 are connected with the members 10 and 11 and are thus in communication with said members and with each other.

Arranged within the water container is a plurality of upright steam reserve pipes 18. For purposes of illustration and making the invention clear, I have shown eighteen of the vertically arranged steam reserve pipes 18, and these pipes may be for instance two and one-half inches in diameter.

15 At the center of the device is a steam chest receptacle 19, which may for illustration be four inches in diameter.

Around each of the pipes 18 is wound a generating coil 20. The coils 20 connect at 20 their lower ends with the member 10 and at their upper ends with the member 11.

The coils 20 may be joined together as at 25 21, and the ends of the members 21 may be inserted into an opening in the member 10.

25 The ends of the members 21 are provided with shoulders 22 and are screw-threaded to receive nuts 23. Between the nut 23 and the inner face of the wall of the member 10, there may be a copper gasket 24 for making 30 a tight joint.

In order to provide access to the nuts 23, I provide a hole 25 in the outer wall of the member 10 opposite the end of the pipe 21, and provide a suitable screw plug 26 for 35 such hole. These openings serve a three-fold purpose; they afford access for assembling and disassembling the generating coils, they permit blowing out of the generating coils by pressure while the coils are assembled, and the cleaning out of lime and sediment from the water container.

It will, of course, be understood that gaskets may be used where desired or necessary.

45 Similarly one or more of the upper coils 20 may be connected to a member 21, which is similarly connected with the member 11.

It will thus be seen that water is fed into the stand pipe and passes into the lower part 50 of the water container, thence through the coils 20 to the upper part of the water container.

Steam is taken from the water container at a large number of points through elbows 55 27, portions of which communicate with and extend directly upwardly from the top of the member 11.

The elbows 27 are connected by fittings 28 with elbows 29 communicating with the upper ends of the steam reserve pipes 18.

60 At the lower ends of the pipes 18 are smaller pipes 30 leading to the lower end of the steam chest receptacle 19. A take-off pipe 31 leads from the top of the steam chest receptacle 19 to the throttle. The lower part

of the steam chest receptacle 19 should be made very heavy and thick.

Below the boiler is a suitable burner 32.

I will now explain the practical operation and some of the advantages of my improved 70 boiler.

Water is supplied to the stand pipe 13 and thence to the water container, comprising the members 10, 11 and 12, and the water is intended to stand within an inch or two 75 of the top of the member 11.

It should perhaps be mentioned that for the sake of compactness, the upper ends of the pipes 18 are substantially level with the upper end of the member 11, while the lower ends of the pipes 18 stand above the lower end of the member 10 to allow clearance for the lower pipes 21 and the pipes 30.

The lower ends of the tubes 20, the lower tubes 21, and the tubes 30 are so arranged that by unscrewing the fittings 28, the pipes 18 and 19 and the tubes 30 may be drawn out from the bottom of the boiler, thus facilitating assembling or disassembling for building and repair. It may be mentioned 80 that by disconnecting the coils from the water container, the boiler may be readily taken apart for repairs or replacement of worn parts.

When the burner is lighted, the water in the generating coils 20 is heated very rapidly and circulates from the lower part of the water container through the coils 20 to the upper part of the water container. The steam is drawn off through vertical portions 95 of the elbows 27 and passes through the elbows 29 to the upright reserve pipes 18 and thence through the pipes 30 to the steam chest receptacle 19 from which it is taken through the pipe 31 to the throttle.

100 There are a large number of advantages which arise from the structure hereinbefore set forth. In all of the boilers of this general type, with which I am familiar, it has been necessary to keep the water at a 105 comparatively low level. This is true because otherwise the steam was taken off wet.

110 In many boilers, when the water is at a low level, it is found that steam is formed in the heating coils and exerts a very strong back pressure, and frequently there is a separation of bodies of waters in the coils with a body of steam between the two bodies, with a result that circulation is not 115 free and the coils are damaged at the point of separation. This separation also results in poor steaming qualities. The separation occurs in some of the coils and not in the others, and the circulation follows the line of least resistance, to-wit, the path in the 120 coolest coil with result that the efficiency of the boiler is very greatly reduced. Where it has been attempted to overcome this objection by the use of larger coils much slower 125 steam generation results.

In the construction of the boiler herein described, I am able to use pipes of small diameter for the generating tubes and to secure a very rapid generation of steam, and with the high water level, the height of the water is such as to prevent any expansion of the kind mentioned in the generating coils.

By permitting water to stand at a point near the top of the water container, it is obvious that the coils 20 are full of water all of the time. This does away to a very great extent with the likelihood of burning out the joints and the small tubes. It will be noted also that the generating coils are such that heat will force water upwardly therein, while in the water container, the water stands in a vertical column and circulation is thus insured. Its weight in the water container prevents any undesirable back pressure in the coils.

Where, however, the water stands near the top of the boiler, there is involved the problem of drawing off dry steam and avoiding the taking of wet steam from the boiler. This problem is solved and the desirable result of securing dry steam is accomplished by taking the steam from the top of the boiler through the upright members of the elbows 27.

The solution of the problem is also contributed to by taking off the steam through a large number of small pipes, which prevent suction and the consequent drawing off of wet steam.

The insuring of dry steam is also accomplished by passing the steam through the upright reserve pipes 18, which are of large size. Because these upright reserve steam pipes 18 are vertical, it is obvious that any moisture that might come into them, would drop immediately to the bottom.

The tubes 30 are subjected directly to the heat of the burner and the steam is thoroughly heated and dried in them. The upright member 19 is also subject to heat from the central portion of the burner and is of large diameter relatively, so that there is no possibility of having moist steam at the upper part of the pipe 19.

It may be mentioned at this time that the bottoms of the pipes 18 may be in the form of relatively thick metal discs welded or otherwise held in so that these bottoms will stand great heat. The same construction may be followed in the receptacle 19, and is illustrated in Figure 3. This also gives to the receptacle 19 and the pipes 18 the benefit of a "hot plate" bottom.

I find that on account of the arrangement of the receptacle 19 and the large number of pipes 30 connected therewith, there is no danger of burning out the small pipes 30, because there is such a large amount of metal, all connected together, that the heat

is quickly conducted from the point where it is directly applied to the pipes 30, to the pipe 19 and the pipes 18.

It will be noted that the distance of travel from each elbow 27 to the upright pipe 19 is the same in all instances. This makes the drawing off of steam through the various elbows 27 even and uniform, and thus contributes to eliminating the taking of any wet steam from the boiler.

Special attention is called to the fact that the arrangement of the boiler is such that the circulation of water is in the natural direction and by the easiest path. The water comes in at the outside of the boiler and then passes inwardly where it is subjected to the greatest heat and upwardly through the heating coils to the upper portions of the boiler, where it may drop straight down. At the discharge ends of the generating coils, both water and steam will issue from the coils. The heavier water goes down while the steam goes upwardly and is taken off through suitable connections or passages to the steam reserve section of the boiler. It will be noted that this action takes place at the extreme outside and top of the boiler, where least affected by the heat of the burner and separation is easy and natural. The pipes 18 offer ample space for reserve steam.

The pipes 18 and receptacle 19 and the tubes 30 form a superheater in which the steam is thoroughly heated and dried. In the pipes 30, all steam is subjected to the hottest part of the burner flame before passing to the pipe 19.

The entire device is very compact, the parts fitting together in a small space.

It will be seen that I have provided a boiler in which the water may stand near the top, whereby there is avoided the likelihood of burning out the heating tubes in the smaller parts, and whereby it is possible to use screw connections that would burn out if they were not covered by water. I can thus use small coils, get rapid circulation and quick steam generation. At the same time, the way the steam is taken off is such that there is no suction of wet steam. The pipes 18 being within the generating coils reflects the heat to the coils. The heat has a clear path to the generating coils.

The steam can travel slowly through a long path through the enlarged pipes 18 and receptacle 19, affording containers for a large reserve of steam, whereby full and complete evaporation is insured.

Another advantage arising from the construction herein shown arises from the use of the plate 15 at the bottom of the stand pipe 13, which may be removed for taking out muck and mud from the stand pipe.

By removing one of the plugs 26 and also

another plug or the plate 15 when the boiler is empty, a steam line can be attached and steam from another source can be used to blow out the boiler and clean it out also.

- 5 It should perhaps be mentioned that the shape of the boiler can be varied as may be desired and need not necessarily be round. It could be built like a horseshoe, elliptical or rectangular with the receptacle 19 varied 10 in shape to insure like distance of travel for all steam.

Changes may be made in the details of the construction and arrangement of the parts of my improved boiler without departing 15 from the essential features and purposes of my invention, and it is my intention to cover by my claims, any modified forms of structure or use of mechanical equivalents, which may be reasonably included within their 20 scope.

I claim as my invention:

1. In a boiler of the class described, a water containing structure, a plurality of 25 superheating and steam reserve pipes arranged within the outline of said container, generating coils surrounding said pipes communicating at their upper and lower ends with the upper and lower portions of the water container, connecting tubes communicating 30 with the top of the water container and the upper ends of said pipes, a central steam receptacle, tubes connecting the bottoms of said pipes with the bottom of said receptacle and a burner under the central 35 portion of said boiler.

2. In a boiler of the class described, a water container, a plurality of upright pipes arranged within the outline of said container, generating coils surrounding said 40 pipes and communicating at their upper and lower ends with the upper and lower parts of said container, tubes leading upwardly from the top of said container, tubes communicating with the upper ends of said 45 pipes, fittings connecting the tubes leading from the container to the tubes leading to the pipes, a central upright receptacle, tubes leading from the bottoms of said first-described pipes to the bottom of said last-described receptacle, the parts being so connected that by disconnecting said fittings, the pipes and receptacle may be withdrawn 50 from the remainder of the boiler.

3. In a boiler of the class described, a 55 central receptacle, a plurality of pipes arranged around said central receptacle, a water container around said pipes, steam generating coils surrounding said plurality of pipes communicating at their upper and lower ends with said water container, tubes leading upwardly from the top of said water container and communicating with the upper ends of said plurality of pipes, tubes 60 communicating with the lower ends of said 65 plurality of pipes and with the lower end

of said central receptacle, the parts being so arranged that the path of travel from the container through each of said plurality of upright pipes to the central receptacle is of the same length as that through every other 70 of said plurality of pipes.

4. In a boiler of the class described, a container comprising vertically spaced annular drums and connecting pipes, a stand pipe communicating with said container, a 75 plurality of upright pipes arranged in circles within said water container, a central receptacle, heating tubes surrounding said plurality of upright pipes communicating at their upper and lower ends with said water 80 container, a tubular passage leading from the top of said water container to the top of each of said plurality of upright pipes, tubes communicating with the bottoms of said plurality of upright pipes and with the 85 lower end of said central receptacle, and a burner below the central portion of said boiler.

5. In a boiler of the class described, a water container, a plurality of upright 90 superheating pipes arranged within the container, steam generating coils surrounding said pipes and communicating at their upper and lower ends with the water container, connecting pipes leading from the upper end 95 of the water container to the upper ends of said first-described pipes, a central upright receptacle, means for conducting steam from said first-described pipes to said central receptacle, and a burner beneath the said 100 boiler.

6. In a boiler of the class described, a water container, a plurality of upright superheating pipes arranged within the outline of said container, steam generating coils 105 surrounding said pipes and communicating at their upper and lower ends with the water container, connecting pipes leading from the upper end of the water container to the upper ends of said first-described pipes, a central upright receptacle, means for conducting steam from said first-described pipes to the bottom of said central receptacle, and a burner beneath said boiler, said water container having screw plugs in its exterior 110 wall opposite the steam pipe coil ends for permitting access thereto.

7. In a boiler of the class described, an upper annular drum, a lower annular drum and pipes connecting the drums, a central 115 steam receptacle, a series of upright pipes communicating at their upper ends with the upper drum and at their lower ends with the lower part of said receptacle, generating 120 coils wound around said upright pipes, communicating at their lower ends with the lower drum and at their upper ends with the upper drum.

Des Moines, Iowa, July 10, 1923.

CARL E. BISHOP.
